[57] CLAIM

The ornamental design for housing for video game machine with wireless receiver, as shown.

DESCRIPTION

FIG. 1 is the perspective view of a design for housing for video game machine with wireless receiver showing my new design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof; and,

FIG. 7 is the bottom plan view thereof.

FIG. 1

FIG. 2

FIG. 3

FIG. 4

FIG. 5

FIG. 6

FIG. 7
